UNITED STATES PATENT OFFICE.

JACOB O. M. SELBERT, OF CHICAGO, ILLINOIS.

TRANSFER TICKET.

Application filed December 1, 1922. Serial No. 604,205.

To all whom it may concern:

Be it known that I, JACOB O. M. SELBERT, a citizen of the United States, residing at Chicago, in the county of Cook and State of Illinois, have invented a new and useful Improvement in Transfer Tickets, of which the following is a specification.

This invention relates to improvements in tickets and relates more especially to that particular type of ticket frequently designated as a transfer or transfer ticket and commonly used on street railways to entitle passengers to transportation over lines intersecting or connecting with that on which a passenger paid his original cash fare.

One of the advantages of my invention is the provision of means whereby one ticket may serve to carry a passenger from the original route over one or more successive connecting or intersecting routes. Heretofore, it frequently has been customary, in cases where more than one change of cars is made by a passenger, to issue a separate transfer ticket for each such change of cars. By the use of my invention, one transfer ticket will serve for any number of changes, thus obviously saving material.

Another advantage of my invention is the provision of means whereby the necessary information on the transfer ticket may be indicated by a minimum of effort on the part of the issuing conductor. For example, it is customary in issuing a transfer ticket to indicate by punch marks the time of issuance, the direction of travel and the name of the issuing route (that is, the route being travelled by the conductor issuing the transfer). Ordinarily it requires four punch marks to give this information, one for the issuing route, one for the direction of travel, and two for the time (one mark to indicate the hour and a second to indicate the minutes). By my improved transfer ticket and method of issuing the same, all of this information may be given with two punches. Of these, one indicates the forenoon or afternoon; and the proper punch mark in this respect may be given to a large number of transfers in advance (the conductor being able to anticipate about how many transfers will be required in a single forenoon or afternoon run). Consequently, there remains only one punch mark that must be put on each transfer by the conductor as the transfer is issued. This results in a great saving of time and

labor and consequently facilitates the issuance of transfers by the conductor.

Other features and advantages of my invention will appear more fully as I proceed with my specification.

In that form of device embodying the features of my invention, shown in the accompanying drawings, Figure 1 illustrates my improved transfer ticket and Figure 2 is a diagrammatic fragmentary view of a street map for the purpose of aiding in explaining my invention.

As shown in Fig. 1, the transfer ticket may bear upon its face the desired matter constituting a valid medium for the transfer of passengers from one car line to another. This matter may be as desired; and I have here shown it as comprising merely the words, "Doe Traction Company." It may also bear a date or other insignia adapted to indicate that it is valid for one day only. I have here shown this information as comprising merely the date "October 31, 1922." It may also bear a serial number, such as 2128727, and such other information as may be desired. The reverse side, not shown, may also contain information regarding the manner of use and such other data as may be desired.

Arranged in the vertical column 10, in suitable rectangles below the upper two (which will be described more in detail hereinafter), I have also printed the information "Through route," "One-half fare," "Emergency," and the like. These rectangles are provided only for exceptional use and will be punched as the occasion requires.

In the upper two rectangles in column 10, I have printed "A. M." and "P. M." as shown. The proper one of these rectangles is punched depending upon whether the transfer is issued in the forenoon or afternoon. In common practice, the issuing conductor may so punch a number of transfers in advance. At noon time (which is ordinarily not a rush time) he can punch approximately enough transfers "P. M." to serve his needs during the entire afternoon. This may be done in the same way for the morning's use. If this is done, each transfer will not have to be punched in this respect as it is issued.

Aside from the information referred to above, the transfer contains twelve principal rectangles 11, as shown. Since these

twelve principal rectangles are similar, I will describe in detail but one.

Each rectangle 11 is divided into sixteen small rectangles 12, there being four vertical rows with four each. The first (at the left) vertical row contains from top to bottom directional indications "N", "S", "E", "W". Above the "N" in the uppermost small rectangle appears a numeral, from 10 to 12, indicating the hour. The top rectangle in the second vertical row contains the number "15" to indicate fifteen minutes past the hour. The uppermost small rectangle in the third vertical row contains the number "30" to indicate thirty minutes past the hour, and likewise the fourth vertical row contains the numeral "45" to indicate forty-five minutes past the hour.

It will be seen, therefore, that there is one large rectangle 11 for each hour and that each of such rectangles has four horizontal rows and four vertical rows, each containing four smaller rectangles. The horizontal rows indicate the direction of travel, as designated by the letters "N", "S", "E", "W", and the vertical rows indicate the quarter hours, as designated by "15", "30" and "45"; the first vertical row indicating the even hour. It is obvious that the horizontal rows may be made longer or may have more subdivisions 12, if it is desired, to indicate smaller fractions of the hour than quarters.

In issuing the transfer, one punch mark put in the proper small rectangle 12 will indicate the direction of travel and also the time of issuance in quarter hours. As explained above, the proper punch mark in "A. M." or "P. M." will indicate the forenoon or afternoon.

I will now explain the method of indicating the issuing route. This may best be understood by referring to the diagrammatic view in Fig. 2 where I have indicated three separate north and south street car routes—"State Street", "Ashland Avenue" and "Wabash Avenue", and three east and west routes—"Madison Street", "47th Street" and "43rd Street". In the use of my invention, each route in the street car system is given some characteristic designating symbol, such as the numerals "1", "2", "3", "4", etc. I have here shown the State Street route as designated by "1", Ashland Avenue by "2", Wabash Avenue by "3", Madison Street by "4", 47th Street by "5", and 43rd Street by "6". Routes "3", "4" and "6" terminate as shown. The conductor on each route is also supplied with a punch which will punch the proper mark designating the route occupied by him. For example, the conductors on State Street carry punches which will punch "1". The conductors on the Ashland Avenue route have punches which will punch "2" and so forth. Therefore, when the conductor issues

a transfer and punches the same, the shape of the punch mark made by his punch will indicate the issuing route.

The advantages of the invention may be better understood by describing a certain course of travel. I will suppose, for example, that a passenger boards a car at X on Wabash Avenue at 2:15 p. m., October 31, 1922 and wishes to go to Y on Ashland Avenue. I will assume as stated above, that the conductor on the Wabash Avenue car has already punched "P. M." in advance on a considerable number of transfers. This conductor, as stated before, is supplied with a punch which will make a punch mark "3". As the passenger pays his fare at X, the conductor takes a transfer (already punched "P. M.") and punches the same "3", as shown. This punch mark being in the large rectangle 11 containing the hour designation "2" and lying in the vertical column with the heading "15", indicates that it was issued at 2:15 p. m. The mark lying in the horizontal column "S" indicates that the direction of travel is south. I will assume that the passenger reaches the intersection of Wabash Avenue and Madison Street at 2:45. At this point he boards a Madison Street car going west and presents his transfer, whereupon the conductor on the Madison Street car punches it with a "4", as shown, and gives it back to the passenger. It is to be noted that the Madison Street car conductor does not issue a new transfer, but merely puts a new punch in the original transfer. This "4" indicates the time and the direction of travel. I will assume that the passenger reaches the intersection at Madison and State Streets at 3:30. He then presents his transfer to the State Street conductor on a south bound car, who punches it with a "1", as shown, thus indicating the time of boarding the State Street car and the direction of travel. I will assume that the passenger reaches the intersection at State Street and 47th Street at 4:00. At this point, the passenger boards a 47th Street car going west; whereupon the conductor punches a "5", as shown. I will assume that the passenger reaches the intersection at 47th and Ashland Avenue at 4:30 p. m. Here he boards a south bound Ashland Avenue car, whereupon his transfer is punched with a "2", as shown. It will be noted that the time and direction are always indicated on the transfer, so that they can easily be determined by the conductor when the transfer is presented, so that there can be no unauthorized use of the transfer. For example, if the passenger at 47th Street and Ashland Avenue presented the transfer to a conductor on a north bound car, such conductor would see at a glance that the passenger's direction of travel was south and west, and consequently would refuse to

honor the transfer for north bound travel. Likewise, if the transfer is presented to any conductor at such a time as to indicate that the passenger had not been continuously travelling, the conductor would refuse to honor it.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent, is:

1. A transfer ticket having marked thereon twelve principal divisions, each being designated by an hour symbol, each of said principal divisions being divided into sub-

divisions, and indicia in connection with the sub-divisions whereby each of such sub- 25 divisions indicates both a fraction of the hour and the direction of travel.

2. A transfer ticket having marked thereon spaces, and indicia in connection therewith whereby each of said spaces indicates 30 both a particular time and direction of travel.

3. A transfer ticket having marked thereon spaces, and indicia in connection therewith whereby each of said spaces indicates 35 a cardinal direction of travel and a fractional hour of time.

4. A transfer ticket having marked thereon spaces in horizontal and vertical columns; and indicia arranged in connection 40 with said columns whereby each space indicates both a particular time and direction of travel.

Witness my hand and seal this 29 day of November, 1922.

JACOB O. M. SEIBERT. [L.s.]
